George H. Fernald, ^{Inventor,}
By Howard P. Denison, ^{Attorney.}

UNITED STATES PATENT OFFICE.

GEORGE HENRY FERNALD, OF NORTHEAST, PENNSYLVANIA.

TRACE-HOLDER.

SPECIFICATION forming part of Letters Patent No. 775,132, dated November 15, 1904.

Application filed August 22, 1904. Serial No. 221,780. (No model.)

To all whom it may concern:

Be it known that I, GEORGE HENRY FERNALD, of Northeast, in the county of Erie, in the State of Pennsylvania, have invented new and useful Improvements in Trace-Holders, of which the following, taken in connection with the accompanying drawings, is a full, clear, and exact description.

This invention relates to improvements in trace-holders.

Trace-holders of the general character illustrated in the drawings accompanying this application are old and well known and set forth in the prior art; but all such trace-holders are so constructed that the projecting end of the movable lever which holds the trace upon the whiffletree engages with the upper face thereof and not only mars the paint and varnish, but embeds itself into the whiffletree, so as to make it unsightly.

My object therefore is to produce a trace-holder so constructed that the projecting finger of the trace-retaining lever will be held out of contact with said whiffletree; and to that end my invention consists in the several new and novel features of construction and operation which are hereinafter described, and specifically set forth in the claims hereunto annexed. It is constructed as follows, reference being had to the accompanying drawings, in which—

Figure 1 shows a side view of my trace-holder secured to the end of a whiffletree, broken away, the trace-retaining lever shown in its raised position in dotted lines. Fig. 2 is a top plan view of the trace-holder detached. Fig. 3 is a side view thereof with the trace-retaining lever raised. Fig. 4 is a cross-section on line X X, Fig. 3.

Similar reference-numerals indicate corresponding parts.

1 is a hollow case forming the base of the trace-holder and is provided with suitable means for securing it to the whiffletree 2, the forward end being provided with a recess 3, in which the trace-retaining lever 4 is adapted to be hinged or pivoted in any suitable man-

ner. The forward end of the case 1 is also provided with a cross-bar 5, usually constructed integral with the base and provided with an opening 6, by which it is secured to the whiffletree.

7 is a strap-spring secured within the base near its lower face in any suitable manner, as by a rivet 8, and extends forwardly to a point 55 adjacent the cross-bar 5 and has its forward end slightly upset, as shown at 9.

The trace-retaining lever 4 has a rear extension 10 and a shoulder 11, both for the purposes hereinafter set forth.

The rearward extension 10 is formed with a flat bearing, so that it will engage with the face of the spring 7, the tension upon the spring 7 holding the lever 4 in its raised position when engaged with the end thereof or holding it in its lowered position when in engagement with its lateral edge 12.

When the lever 4 is brought down to its horizontal position, as shown in Fig. 1, for the purpose of retaining the trace, the lug 70 or shoulder 11 engages with the cross-bar 5, and thereby holds the free end 13 of the lever 4 out of engagement with the whiffletree, as shown in Fig. 1.

Having thus described my invention, what I claim, and desire to secure by Letters Patent, is—

1. In a device of the character described, a long hollow base adapted to be secured to the whiffletree and having a cross-bar at its front end, a trace-retaining lever pivoted in said base and having a shoulder adapted to engage with the cross-bar in the base for the purpose of holding the free end of said lever out of engagement with the whiffletree.

2. In a device of the character described, a hollow case having a cross-bar at its front end and means for securing it to the whiffletree, a strap-spring secured in the base of said case, a lever having a rear extension 90 adapted to engage said spring either in its raised or depressed position, and a shoulder adapted to engage with the cross-bar for the purposes specified.
